UNITED STATES PATENT OFFICE.

JOHN J. VARUSKY, OF MINNEAPOLIS, MINNESOTA, ASSIGNOR TO CARTER-MAYHEW MANUFACTURING CO., OF MINNEAPOLIS, MINNESOTA, A CORPORATION OF MINNESOTA.

RECLAIMING ATTACHMENT FOR SCALPERS.

Application filed February 3, 1927. Serial No. 165,563.

My invention provides a simple and efficient grain reclaiming attachment or device adapted for use in connection with scalpers and particularly designed for use in connection with scalpers of the type disclosed and claimed in Letters Patent of the United States No. 1,568,267, issued to Clarence W. Carter as inventor of date January 5, 1926.

In the use of such scalpers, all large objects, such as sticks, pieces of paper, leaves, nails and other large foreign objects, will be carried out of the commingled grain and usually deposited directly on the floor of the room in which the device is installed. In practice, it has been found that some good grain will be carried over with the tailings, and it has been noted that the chief cause of this carrying over of the good grain is the presence of leaves, pieces of paper or other flat objects in the commingled grain. The amount of good grain that will be thus carried over with the tailings is very small as compared with the total amount of good grain passed through the scalper, but in a machine of large capacity, the amount of good grain carried over in the course of a day has been found to be well worth saving and, hence, it has been the practice in removing the tailings to sift the same by hand and to thereby reclaim as much as possible of the carried-over good grain.

My invention provides an automatic reclaiming separator or device for reclaiming the good grain from the tailings, and the preferred form is illustrated in the accompanying drawings. In these drawings, this reclaiming separator is shown as applied to receive from a rotary scalper of the Carter type above identified, and which scalper is applied in connection with an aspirator, which latter, however, per se, constitutes no part of my invention.

Referring to the drawings, wherein like characters indicate like parts throughout the several views:

Fig. 1 is a front to rear vertical section taken through the scalper, aspirator, and reclaiming separator;

Fig. 2 is a transverse vertical section taken approximately on the line 2—2 of Fig. 1, some parts being broken away and some parts being removed;

Fig. 3 is a horizontal section taken approxi-

mately on the irregular line 3—3 of Fig. 2, some parts being shown in full; and

Fig. 4 is a vertical section taken approximately on the line 4—4 of Fig. 3.

For the present illustration, we will assume that the material to be separated is wheat, which contains some oats, small seeds and various other foreign objects, such as pieces of paper, leaves, nails, sticks, straws and the like. In the arrangement illustrated, this commingled stock *y* is assumed to be delivered from the spout 5 into a hopper 6 from which the discharge is controlled by a gate 7. The stock discharged from the hopper 6 is delivered to a large-mesh rotary scalping screen 8 of cylindrical form secured to heads 9 carried by a shaft 10 journaled in suitable fixed bearings 11 on the sides of the machine. Clearly disclosed in the prior Carter patent above identified and as already indicated herein, the meshes or openings in the rotary scalping screen are many times larger than sufficient to pass freely therethrough all of the different grains such as wheat, oats, rye, barley and the like, which are to be separated from coarse materials such as sticks, nails, leaves, pieces of paper and the like. The cylindrical scalping screen 8 works in an open housing arranged to receive from the hopper 6 and having a hopper-like lower portion 12, the discharge from which is, as shown, controlled by an adjustable gate 13 and a feed roller 14. Secured to the heads 9 and located within the screen 8 are overlapped restraining baffle plates 15 that restrict the flow of the grain substantially as indicated in Fig. 1, when said screen is rotated in a counter-clockwise direction in respect to said view. All of the large particles, such as sticks, nails, leaves, pieces of paper, straw and the like, will be carried over and discharged from the exterior of the screen 8 on the front side of the machine, to wit: at the left in respect to Fig. 1.

The commingled stock cleared of the tailings will be delivered into a lower hopper-like housing 15 and from thence to a discharge spout 16; but on its way to the housing 15, such stock will be subjected to suction from an air blast produced by an aspirator, which, in so far as it is shown, comprises a casing 17 and an air outlet tube 18, which latter may be assumed to be connected to the inlet of a suction fan or blower. The hopper-like

housing 15 has an end wall 15' which connects with the side wall of the catch trough 19 as shown in Fig. 1.

The tailings, which, as already noted, are carried over by the rotary screen 8, will be delivered to the reclaiming separator. This device may be permanent or detachable and is capable of modification but, as shown, comprises a catch trough 19 extended transversely of the machine just in front of the screen 8 and in position to receive the tailings. This trough, as shown in Fig. 1, is rigidly secured to the lower housing 15 through the medium of the wall 15' and it is provided with an im-
5 perforate deck-like bottom 20 which, as shown in Figs. 2, 3 and 4, extends from the left-hand end of the trough and delivers into the upper portion of a receptacle afforded by the upper end of a reclaiming spout 21. The separating belt, preferably a perforated rubber belt 22, is arranged to run over pulleys 23 and 24 secured, respectively to shafts 23^a and 24^a journaled in suitable bearings on the extended sides of the trough 19. The upper portion of this belt 22 runs on the deck-like bottom 20 of the trough and passes over the open upper portion of the reclaiming trough 21. The shaft 24^a carries a ratchet-like cam 25 that operates on the free end of an arm 26 secured to a rock shaft 27 journaled in the depending sides of the trough 19 and located in the receiving end of the spout 21. Rigidly secured to this shaft 27 is an approximately L-shaped belt-vibrator or arm 28, the transverse free portion of which is positioned to strike against the under surface of the upper portion of the belt 22 at a point close to the left-hand side of the spout 21, directions being taken in respect to Fig. 4.

40 A coiled spring 29, attached to the arm 26 and adjustably anchored to the adjacent depending side of the spout 19, keeps the free end of the arm 26 engaged with the cam 25 and causes the free end of the arm 28 to strike the belt each time that a lug of the cam 25 passes from under the free end of said arm 26. Secured to the inner plate of the trough 19 and located between the upper and lower runs of the belt 22 is an inclined plate 30 that directs the material passed through the belt onto the inclined bottom of the lower housing 15.

In the machine shown, the rotary screen 8 is given its rotary motion, the belt 22 is given its traveling motions, and the belt vibrator 28 is given its oscillatory movement through the following driving connections: The power is transmitted through a sprocket chain, not shown, which runs over a sprocket 31 on the shaft 10 of the rotating screen, and said shaft 10 is provided with another sprocket 32. A sprocket chain 33 runs over the sprocket 32 and over a sprocket 34 on a short countershaft 35 journaled in suitable bearings 36, (see Fig. 3), secured to the ad-

jacent side plate of the trough 19. The shaft 35 is provided with a bevel pinion 37 that meshes with a bevel gear 38 on the pulley shaft 24^a.

Following out the illustration of the cleaning of wheat, it is understood that the wheat commingled with more or less oats, rye, barley, small seeds and dust, will pass through the scalper into the lower hopper 12, and on its way to the discharge spout 16 will be subjected to an upward draft produced by suction, so that the light particles and dust will be removed therefrom. However, the main body of the stock, consisting of the wheat, oats, rye, barley, and small seeds, will pass out through the spout 16 and the separation of such other materials from the good wheat may be accomplished by any suitable means, not necessary for the purpose of this case to consider. The tailings, consisting, as already assumed, of leaves, pieces of paper, sticks, nails, straw and the like, together with a comparatively small part of the good wheat and possibly some still smaller percentage of oats and other materials foreign to the wheat, will be delivered into the trough 19 and onto the perforated belt 22. Materials such as wheat will get into the perforations of the belt and will be carried into the receiving end of the reclaiming spout 21.

To cause grain lodged on the belt between the perforations to flow through the belt perforations and hence to pass through the belt into the receiving spout, the vibrator 28 is caused to strike the belt with a rapidly repeated series of taps at the place where the belt is exposed above the receiving end of the spout.

Preferably, the perforations in the belt are large enough to receive and pass therethrough wheat, oats, rye, barley and in fact all good grain, but not large enough to pass therethrough the coarse or larger foreign materials usually designated as tailings. Of course the perforations may be made of any desired size as for example, of a size or shape that would pass therethrough only wheat but not oats, rye or barley. Obviously, there is no objection to returning to the main stream of grain all good grain such as wheat, oats, rye or barley inasmuch as the main stream of stock will be subsequently subjected to a separator when it is desired to separate the wheat from the other grains.

A machine known to the trade as the Carter-Mayhew disc separator would be efficient for separating the wheat from the said other grains.

The efficiency of the machine above described has been demonstrated in actual practice.

What I claim is:

1. A scalping screen continuously movable in a definite direction and provided with openings much larger than required to freely

pass therethrough all grains such as wheat, oats, barley and rye, whereby the body of commingled grain will pass freely through said scalping screen but large long objects 5 such as straw, sticks, nails, leaves and pieces of paper will be carried over said scalping screen carrying therewith a small amount of good grain, in combination with a reclaiming screen receiving the materials carried over by 10 said scalping screen and having openings through which the grain can pass but through which the foreign objects such as straw, sticks, nails, leaves and pieces of paper cannot pass, whereby the grain is saved from 15 the said coarse scalpings, and a grain receiving hopper common to said scalping screen and said reclaiming screen.

2. A rotary drum-like scalping screen mounted on an approximately horizontal axis 20 continuously movable in a definite direction and provided with openings much larger than

required to freely pass therethrough all grains such as wheat, oats, barley and rye, whereby the body of commingled grain will 25 pass freely through said scalping screen but large long objects such as straw, sticks, nails, leaves and pieces of paper will be carried over said scalping screen carrying therewith a small amount of good grain, in combination 30 with a trough arranged to receive the materials carried over by said scalping screen and provided with an imperforate deck-like bottom, a perforated reclaiming belt movable over said deck and beyond the end of the same and operative to pass grain therethrough but to carry off the foreign materials such as straw, sticks, nails, leaves and pieces 35 of paper, and a grain receiving hopper common to said scalping screen and reclaiming device.

In testimony whereof I affix my signature.

JOHN J. VARUSKY.
